BALLING MACHINE

Filed June 30, 1928

UNITED STATES PATENT OFFICE

JAMES JONATHAN CALDWELL, OF CHICKAMAUGA, GEORGIA, ASSIGNOR TO STANDARD-COOSA-THATCHER COMPANY, OF CHATTANOOGA, TENNESSEE, A CORPORATION

BALLING MACHINE

Application filed June 30, 1928. Serial No. 289,433.

This invention relates to balling machines. It is an object of the invention to provide an improvement over machines of this character in devices for moving the thread longitudinally along the ball, and particularly an improvement of the cam which operates the thread moving means.

A further object is to provide an improvement in balling machines whereby the machine may be operated at a much greater speed than machines heretofore known.

In machines of this character it has been customary to provide a double screw for moving a lever for carrying the thread along the ball of the machine. Such double screws as have heretofore been used have proved unsatisfactory in that the groove on the screw would not always reverse the lead properly with a result that the machine would be stalled. I overcome this difficulty by providing a groove around a roller and this provides a cam track for a cam follower which moves the thread shifting lever. This groove lies in a plane oblique with respect to the axis of rotation of the shaft upon which the roller is mounted. This provides a positive cam track which cannot fail to function properly during operation of the machine.

The maximum speed possible on the old style baller was 100 yards per minute, and the usual operating speed was approximately 65 yards per minute. The maximum speed on my machine is 500 yards per minute and it is being operated at a speed of approximately 200 yards per minute. This machine therefore has greatly increased production over the former machines.

Referring to the accompanying drawings which are made a part hereof and on which similar reference characters indicate similar parts,

Figure 1 is a plan view of a balling machine showing my invention,

Figure 2, a sectional elevation on line 2—2 of Fig. 1,

Figure 3, a detail showing a braking device,

Figure 4, a detail view of the cam follower,

Figure 5, a detail view showing means for adjustably securing the pivot point of the thread shifting lever, and

Figure 6, a detail of the bracket carrying the thread trumpets.

In the drawings numeral 10 indicates the base of the balling machine having on each side a forward bracket 11 for supporting the drum on which the yarn is wound and the associated elements and rear standards 12. In the standards on the rear of the machine a shaft 13 is mounted. This shaft carries a cam which is composed of two wheels 14 and 15 mounted upon a hub 16 on the shaft 13. The elements 14 and 15 may preferably be two wheels mounted obliquely with respect to the axis of the shaft 13 and spaced apart so as to provide a cam groove or track.

Secured at their ends on the base of the machine are two rods or shafts 17 and 18. These rods provide a track for a sliding cam follower 19. This follower comprises a sleeve 20 adapted to slide longitudinally along the rod 17. The sleeve has an arm 21 upon which a roller 22 is mounted. The outer end of the arm 21 has a U-shaped notch 23 therein for sliding engagement with the rod 18. The cam follower 19 has a lug 24 with a depending pin 25 for pivotally securing upon the lug a lever arm 26 to be further described.

The shaft 13 and the cam mounted thereon are rotated by means of a chain 27 connecting pinion 28 and a large pinion 29 on the outer end of the shaft 13. Mounted upon the shafts 30 and 31 on the forward part of the machine are rollers 32 and 33. A gear 34 on the shaft 31 drives the shaft 30 by means of a gear 35 on the outer end of the latter shaft and an intermediate driving gear 36. A gear 37 on the shaft 31 drives a gear 38 on a shaft 39. This latter shaft has mounted thereon the pinion 28 above mentioned. The shaft 31 is operatively connected to any suitable source of power and provides the main driving shaft for the machine.

A roller 40 is loosely mounted to rest between the cylinders 32 and 33. This roller provides the base upon which the thread is wound and is rotated by frictionally engaging the rotating drums between the peripheries of which it is mounted. The drum 40 is mounted upon a shaft 41. This shaft has at each end a bracket 42 which has secured upon its upper end a

bearing 43 in which is positioned a plunger 44. This plunger has on its lower end an arcuate bearing for engagement with the shaft 41. A spring 46 positioned between the bearing 45 and the bearing 43 provides resilient means for holding the bearing 45 in engagement with the shaft 41.

The lower end of the bracket 42 has secured thereto a strap 47. This strap extends around a cam 48 and is secured thereto. The cam is mounted upon a shaft 49. The outer end of this shaft has a drum 50 mounted thereon. Pins 51 and 52 secured in the supporting standard 11 of the frame provide pivot points for brake bands 54 and 53 and a lever 56. The lever 56 pivotally mounted upon the pin 52, has an adjustable weight 57 on its outer end. As may be readily seen in Figure 3, the weight 57 by means of brake bands 54 and 53 holds the drum 50 under constant friction to prevent its rotation.

A trumpet supporting standard 58 is slidably mounted upon shafts 59 and 60 secured at their ends in the frame of the machine. This standard comprises an integral sleeve 61 adapted to slide on the shaft 59. This sleeve has a forwardly extending lug 62 which is pivotally secured by a pin 63 to the arm 26. On its upper end the standard 58 has a sleeve 64 which slides upon the shaft 60 and is guided thereby. The upper end of the standard 58 has a cross arm 65 secured thereon. Upon the outer ends of this cross arm are thread carrying trumpets 66 and 67. Intermediate the outer trumpets is a central trumpet 68. The arm 26 is pivotally mounted at 69 upon a bar 70 which is removably secured by bolts 71 to the base of the machine. As shown in dotted lines and in Figure 5, the bar 70 may be moved and secured to the frame at 72 so that the pivot point 69 pivots at 73 and thus vary the throw of the forward end of the lever 26 which carries the thread carrying trumpets.

The operation of the device is as follows: When winding a single ball, a thread is passed through the central trumpet 68 and the bar 70 is secured in the position shown in full lines in Figure 1. The machine is then driven by power applied to the outer end of the shaft 31. The drums 32 and 33 are rotated and by frictional engagement with the thread carrying drum the latter is rotated, the drum being held in frictional engagement with the peripheries of the drums by means of the strap 47 and the cam 48 which is held sufficiently by the brake band 54 to prevent loose rotation. Driven through the gears 37, 38, pinion 28, belt 27 and gear 29, the cam wheels 14 and 15 are rotated. The cam follower roller 22 engaging between the peripheries of the cam wheels 14 and 15 is moved back and forth along the shaft 17. This swings the arm 26 backward and forward to move the thread carrying

trumpets backward and forward along the spool upon which the thread is wound. Springs 75 and 76 secured upon collars 78 and 79 on the shaft 17 provide for cushioning the stroke of the lever 26 at each end of its travel.

When it is desired to wind shorter spools the bar 70 is secured upon the base 10 at the holes 72 and the pivot 69 is secured at 73. This shortens the throw of the forward end of the arm 26 to provide for depositing the thread upon a shorter spool. When operating this form of the machine the thread is passed through the trumpets 66 and 67 and is wound upon two spools placed end to end upon the shaft 41.

It will be obvious to those skilled in the art that various changes may be made in my device without departing from the spirit of the invention, and I, therefore, do not limit myself to what is shown in the drawings and described in the specification, but only as set forth in the appended claims.

Having thus fully described my said invention, what I claim as new and desire to secure by Letters Patent, is:

1. In a balling machine a frame, a pair of parallel cylinders rotatably mounted thereon, a spool mounted above said cylinders and adapted to rest upon and be rotated thereby, a bracket having mounted thereon thread carrying trumpets for laying thread along said spool, a pivoted lever supporting said bracket, a shaft supported by the frame of the machine, a pair of wheels mounted obliquely upon said shaft and spaced apart to provide a cam track between their peripheries, and a cam follower upon said lever adapted to engage between the said wheels whereby rotation of said cam will reciprocate said thread carrying trumpets longitudinally of said spool to lay the thread upon the spool, substantially as set forth.

2. In a balling machine a pair of parallel cylinders rotatably mounted on a machine, a thread supporting spool supported upon the peripheries of said cylinders, means for holding the said spool in contact with the peripheries of the cylinders to provide frictional drive between the cylinders and the spool comprising a strap resiliently secured to a shaft on the said spool, a cam, the said strap being wound around the cam, and means for holding the cam under a constant friction, substantially as set forth.

3. A balling machine comprising a frame, a pair of parallel cylinders rotatably mounted thereon, a spool mounted above the cylinders and resting upon them to be driven thereby, a bracket slidably mounted on transverse bars on the frame of the machine, said bracket supporting thread carrying trumpets for laying thread along the spool, a lever pivotally mounted on the frame of the machine and connected to the said bracket, a shaft supported in

the frame of the machine and having a pair of wheels mounted obliquely thereupon and spaced apart to provide a cam track between their outer edges, a cam follower slidably mounted on transverse bars in the frame, the cam follower having a roller engaging the track between the peripheries of the wheels, the said cam follower being connected to the end of the said pivoted lever, whereby rotation of the said wheels will cause a swinging motion of the lever to move the trumpets to lay thread along the spool, substantially as set forth.

4. In a balling machine, means for laying thread along one or more spools comprising a lever, a bracket mounted upon said lever, thread carrying trumpets mounted upon said bracket, means for oscillating said lever comprising a pair of wheels obliquely mounted upon a rotatable shaft having a cam track formed by the peripheries of the wheels, a cam follower upon the said lever adapted to engage the cam track, and means for selectively pivoting the said lever to change the throw of the thread carrying trumpets along the spool to lay the thread along a single large spool or two or more small spools, substantially as set forth.

In witness whereof, I have hereunto set my hand at Chattanooga, Tenn., this 19th day of June, A. D. nineteen hundred and twenty-eight.

JAMES JONATHAN CALDWELL.
